CHARLES A. RENNAU, OF HANNIBAL, MISSOURI. ASSIGNEE OF ONE-HALF TO JOHN W. SHELBOURNE, OF HANNIBAL, MISSOURI.

GRIPPING-TOOL FOR PACKING RINGS.

1,224,416.

Specification of Letters Patent

Patented May 1, 1917.

Application filed November 2, 1916. Serial No. 129,204.

To all whom it may concern:

Be it known that I, CHARLES A. RENNAU, a citizen of the United States, residing at Hannibal, in the county of Marion and State 5 of Missouri, have invented certain new and useful Improvements in Gripping-Tools for Packing-Rings, of which the following is a full, clear, and exact description, reference being had to the accompanying drawings, 10 forming a part hereof.

My invention has relation to improvements in gripping tools for packing rings; and it consists in the novel features of construction more fully set forth in the specification and pointed out in the claims.

The object of my invention is to provide a tool by means of which a piston-head packing ring of the resilient split-band type may be seized or gripped and deposited in 20 the piston-head groove designed to receive the same after which the piston with its ring may be readily inserted or pushed into the cylinder with a minimum loss of time and a minimum amount of manipulation. A 25 further object is to provide a tool of the character described which is quickly adjustable to the size of ring desired; one which will clamp the ring firmly to the piston; one from which the piston with its ring may 30 be quickly forced from the tool into the cylinder, and one possessing further and other advantages better apparent from the following detailed description of the invention in connection with the accompanying 35 drawings in which—

Figure 1 represents a perspective of a multiple gasoline engine cylinder showing my invention applied thereto; Fig. 2 is a plan of a split-band packing ring showing the 40 application of my gripping tool thereto before the same has been contracted; Fig. 3 is a similar view showing the tool in gripping or contracted position and showing the packing ring closed; Fig. 4 is an edge view 45 of Fig. 3; Fig. 5 is an enlarged side elevational view of the short lever arms of the handle or grip and the parts attached thereto; and Fig. 6 is an enlarged cross-section on the line 6—6 of Fig. 3.

Referring to the drawings, C, represents 50 a cylinder of a conventional type of gasoline engine and P, the piston or piston-head operating therein as well understood in the art. These piston heads are provided with annular grooves which receive the packing 55

rings R; a prevailing form of such ring being a resilient split band whose terminals are normally separated by a space a allowing the ring to be contracted while being inserted in the groove designed to receive it. The groove itself does not appear in the drawings, being filled with the ring R in Fig. 1, illustration thereof being however unnecessary since the same is well understood in the art.

The invention comprises a handle or grip composed of the long lever arms 1, 1, and short lever arms or jaws 2, 2, on the order of a pair of pliers, one of the short arms having pivotally coupled to the free end thereof of a pivot block or anchor member 3, provided with a pair of ears or lugs 4 through which and through the lever arm 2 passes the hinge pin 5. The base of the block 3 is riveted or otherwise secured to one end of a contractile clamp-band 6 which is of sufficient dimension to accommodate or span rings ranging in size say from two and one-half to six inches in diameter (or rings ranging between any other predetermined limits). The free end of the opposite short lever arm 2 is pivotally coupled by means of a pin 5' between the adjacent terminals of a pair of links 7 whose opposite ends are pivotally connected to a pin 8 passed loosely through the outer terminal loop h of a link 9, the inner end of said link being pivotally coupled by means of a pin 10 between the lugs or ears 11 of a sliding block 12, as shown to best advantage in Fig. 5. The link 9 is formed with a gripping nose or cam n about the axis of the pin 10, said nose operating as a dog for gripping or biting the band 6 and clamping it between the nose and the base of the block 12, with a closing movement of the lever arms of the handle or grip, as will more fully appear later on. Secured to the lever arm 2 carrying the links 7 is one end of a flexed spring 13 which curves around the ends of the said lever arms, the free end of the spring bearing against the rear edges of the said links. The handle is provided with the usual handle-spring or grip-spring S as well understood in the art.

The operation may be briefly described as follows: The anchor 3 is secured to one end of the contractile clamp-band 6, the body of the band passing more or less loosely between the block 12 and the nose n of the

gripping dog or cam formed on the lever 9. Normally, the resilience of the spring 13 engaging the links 7 causes the latter to exert sufficient draft on the lever 9 to maintain 5 the nose *n* thereof well engaged with the band 6, a closing movement of the levers driving the nose forcibly against the band and effectively gripping the same between the nose and the block 12. With one end of 10 the band thus anchored to the block 3, and an intermediate portion gripped between the nose *n* of the dog and the sliding block 12, it is apparent that if we first adjust the band 6 so as to just encompass the packing 15 ring R (Fig. 2) while the latter is maintained opposite the groove of the piston-head and then close the levers 2, 2, to the position indicated in Fig. 3, the ring will be closed or contracted so as to enter the 20 groove of the piston. By now lowering the piston with its ring into the cylinder until the ring comes partially opposite or within the walls of the cylinder, the grip on the ring may be released and the piston and 25 ring pushed into the cylinder the entire distance as clearly obvious from Fig. 1 which shows the ring in the piston-head groove, and the piston shoved far enough into the cylinder to permit the grip on the ring to be 30 released and allow both piston and ring to be shoved into the cylinder. In inserting the piston-head with the ring held contracted by the tool so as to remain in the groove of the piston, a slight pressure on the end of 35 the piston will force the piston and ring through the clamp into the cylinder after which, and when the ring comes opposite the cylinder walls, the grip of the tool may be slackened and the tool pulled away from 40 the piston. To quickly adjust the band 6 to rings of different diameters it is desirable to overcome the natural grip or bite of the nose *n* on the band so that the latter may be freely and quickly adjusted or moved between the nose and block 12 to a point where 45 it will just embrace the ring while the latter is in its expanded position (for example in Fig. 2). To accomplish this the operator seizes the members 7 and 9 between his 50 thumb and forefinger so as to oscillate them toward one another (see for example the dotted position of the parts in Fig. 5), whereby the dog or nose *n* will be rocked away from the band 6, leaving the latter to 55 be slipped between the nose and block 12 to any degree of contraction or enlargement depending on the diameter of the ring to which it is to be initially adjusted. Once the band is adjusted, the closing of the levers 2, 2, will contract it so as to cause the 60

same to enter the piston groove designed to receive it. Obviously, the tool is not limited in its application for handling rings of pistons of gasoline engines, but may be employed for a variety of purposes, and in 65 connection with rings of pistons generally. The details may in a measure be departed from without in any wise involving a departure from the spirit of my invention. The contractible band 6 may be said to have one 70 relatively fixed end, and one free end, and adapted to be seized at any desired point (within certain limits of course) between these ends, and the fixed end and the point thus seized drawn together and the band 75 contracted.

Having described my invention what I claim is:

1. In a tool of the character described, a contractible band, a pair of pliers, a block 80 permanently anchored to one end of the band and pivotally coupled to one of the plier jaws, a second block slidable along the band, a dog coöperating with said sliding block and positioned to bring the band between the dog and block, links connecting said dog to the opposite jaw of the pliers, and a spring exerting a draft on the links for normally forcing the dog into engagement with the band and causing the band to 90 be gripped between the dog and block.

2. A clamping tool for expansible piston rings comprising a contractible band adapted to embrace the ring, a pair of pliers, a block anchored to one end of the band, and 95 provided with ears pivotally coupled to one of the jaws of the pliers, a block slidable along the band and provided with a pair of lugs or ears between which the band is confined, a lever pivoted between the lugs and 100 provided with a cam or nose for engaging the band, links coupling the opposite jaw of the pliers to the cam lever, a flexed spring having one end fixed to the jaw and its free end engaging the links to cause the same to 105 exert a draft on the cam lever to normally force the cam against the band and frictionally hold the latter between the cam and the sliding block, the cam being forcibly driven against the band with a closing movement of the plier jaws whereby the band is firmly gripped between said cam and block, and contracted to close the packing ring 110 confined within it.

In testimony whereof I affix my signature, 115 in presence of two witnesses.

CHAS. A. RENNAU.
